5 Claims. (Cl. 179—100.4)

1

This invention relates to electro-acoustical devices of the type in which vibration of a member at sound frequencies produces corresponding variations in electrical current in an associated electrical circuit. The invention relates more especially to microphones and phonograph pickup devices and systems in which vibration of a member produces amplitude modulation of a high frequency wave. It is a primary object of the present invention to provide an improved signal translating apparatus of this type.

An object of the present invention is to provide an improved phonograph pickup system especially useful with phonographs, radio phonograph systems or the like.

Another object of the present invention is to provide an improved arrangement of an oscillating circuit with a phonograph pickup for producing, demodulating and amplifying high frequency signals modulated in amplitude in accordance with vibrations imparted to the pickup.

Still another object of the present invention is to provide an improved phonograph pickup system which has none of the disadvantages residing in the use of crystals because of temperature, humidity, etc.

Yet another object of the present invention is to provide improved phonograph pickup structures particularly suitable for use with a record of the so called "constant velocity cut" in which the amplitude of the cut decreases 6 decibels per octave.

Still a further object of the present invention is to provide an improved phonograph pickup system which produces a minimum amount of "needle chatter," a minimum amount of record wear and which has a substantially flat frequency response characteristic curve at least within the range of 2000 to 4000 cycles, with the characteristic curve dropping markedly at frequencies above 4000 cycles per second.

Yet a further object of the present invention is to provide an improved vibratory element for producing amplitude modulated waves which element is substantially insensitive to stray magnetic fields, for example, from either an alternating current motor for driving a phonograph or from a power transformer.

Still a further object of the present invention is to provide an improved vibratory element associated with a frequency determining element of a high frequency electrical oscillating system wherein movement of the vibratory element pro-

2

duces no change in the frequency of the oscillating system but does produce substantial changes in the amplitude of oscillations in the system.

5 The features of the present invention which are believed to be novel are set forth with particularity in the appended claims. The present invention itself, both as to its organization and manner of operation, together with further objects and advantages thereof may best be understood by reference to the following description taken in connection with accompanying drawings in which:

Fig. 1 illustrates a circuit arrangement embodying certain features of the present invention.

Fig. 2 illustrates a vibratory member particularly useful in the arrangement of Fig. 1.

Figs. 3-5 illustrate details of a phonograph pickup construction particularly useful in the arrangement of Fig. 1, Fig. 3 being a section taken substantially on line 3—3 of Fig. 4.

Fig. 6 illustrates certain frequency response characteristics obtained with the use of apparatus described herein.

Fig. 7 illustrates a modified pickup structure for use in the arrangement of Fig. 1, Fig. 7 being a sectional view taken on a line similar to line 3—3 of Fig. 4.

Figs. 8 and 9 illustrate modified circuit arrangements embodying the present invention.

The apertures described herein, illustrative of other apparatus which may embody the present invention, is arranged in Fig. 1 to transform intelligence recorded on a movable record medium 1 into suitable current variations of audible frequency in a utilization or amplifying device 2.

10 The intelligence on record disc 1 is in the form of laterally cut impressions of undulating character in which a suitable stylus 3 travels as the record disc 1 is rotated by conventional means whereby a vibratory member 4 attached to the stylus is vibrated to produce corresponding changes in the impedance of an inductance element 5 magnetically coupled to the vibratory member.

Inductance element 5 whose effective resistance or inductance value may be cyclically altered by corresponding movement of stylus 3 constitutes one element of a single frequency determining circuit 5, 6, 7 in an oscillatory circuit including an electron discharge device 8—shown in Fig. 1 as a twin triode. As will be evident later from the description which follows, the first triode section of discharge device 8 with its 55 associated circuits functions not only as an oscil-

latory device but also as a combined demodulating and amplifying device.

The series circuit formed by the serially connected inductances 5 and 6 is connected in parallel circuit relationship to condenser 7 to form the parallel tuned circuit 5, 6, 7, one terminal of that tuned circuit being connected through condenser 9 to the output electrode or anode 10 of the first triode section of device 8, the other terminal of the tuned circuit being connected through condenser 11 to the control grid or input electrode 12 of the first section of device 8 and the junction point of inductance elements 5 and 6 being connected to the common grounded cathode 13. Grid leak resistance 14 connected between grid 12 and cathode 13 serves a plural purpose as will become evident from the description which follows.

Space current for anode 10 is supplied from voltage source 15 which has its positive terminal connected through a load resistance 16 to anode 10 and its negative terminal connected to the grounded cathode 13.

The operation of the electrical circuit thus far described in connection with Fig. 1 is as follows. Device 8, including anode 10, control electrode 12 and cathode 13 sustains an oscillatory current of constant amplitude in the tuned circuit 5, 6 and 7 in well known fashion when the vibratory member 4 does not move. Movement of vibratory member 4, for example, by stylus 3 traveling in the sound track of a conventional phonograph record groove, produces cyclical changes in the impedance of inductance element 5 to change the amplitude of oscillatory current flowing in the tuned circuit 5, 6, and 7 whereby amplitude modulation of such oscillatory current is produced. One important feature of the present invention is that device 8 including anode 10, electrode 12 and cathode 13 serves to produce simultaneously modulation components of the amplitude modulated wave across grid leak 14 and to amplify such components whereby they appear in amplified form on the anode 10.

Such amplitude modulation components are then applied to the second section including control grid or electrode 17, anode 18 and common cathode 13 of the twin triode device 8 wherein the detected modulation components are further amplified.

Anode 18 is supplied with space current from the positive terminal of source 15 through resistance 19 and the control grid 17 is maintained at a suitable negative continuous potential with respect to cathode 13 by connecting grid leak resistance 20 between grid 17 and ground.

Amplified modulation components derived from the generated oscillation appear at anode 10 and are transferred to the control grid-cathode circuit of device 18, 17, 13 through the series circuit comprising, in turn, filter resistance 21, isolating and coupling condenser 22 and filter condenser 23, grid 17 being connected to the junction point of condensers 22 and 23, the other terminal of condenser 23 being connected to grounded cathode 13. Filter condenser 23 has relatively small reactance at the frequency of oscillatory current generated in the stage 10, 12, 13 so that substantially all of the amplified voltage appearing at anode 18 is of a frequency corresponding to the frequency of vibration of the vibratory member 4. The amplified voltage is applied to device 2.

The vibratory member 4 of Fig. 1 magnetically coupled to coil 5 is preferably of high resistance conductive material and in one form of the

present invention is .004" thick and is stainless steel known in the trade as American Iron and Steel Institute type No. 302. Stainless steel type 302 contains about 18% chromium, about 8 or 9% nickel, about 0.08 to 0.2% carbon, traces of manganese, silicon, phosphorus, sulphur and copper and the remainder iron. Stainless steel type 304 is preferred because it is substantially non-magnetic and contains less carbon. This type is preferred for it has been found that, by using such material, a minimum amount of 120 cycle hum is introduced into the pickup from nearby motor driven turntables, transformers, etc. It has been found that stray 60 cycle fields shift the working point on the magnetization curve of the vibratory member with the result that the inductance and effective resistance of the coil 5 coupled thereto change. Such change produces undesirable amplitude modulation of the oscillating circuit. For these reasons where stray alternating magnetic fields are present the material preferably possesses high resistance and low permeability. In such case desirable modulation is produced substantially entirely by eddy current loss in the high resistance material, and the modulation is substantially unaffected by variations of permeability of member 4 in the presence of such stray fields.

30 Vibration of a member of non-magnetic, high resistance conductive material in the vicinity of inductance element 5 causes amplitude modulation in the oscillatory current because (1) the quality factor or "Q" of the inductance element 35 is changed cyclically and (2) the amount of feedback voltage from anode 10 to grid 12 is changed cyclically due to cyclical change in the magnitude of inductance in the element 5, so that when the impedance of coil 5 is altered the feedback factor is altered in such a way that amplitude modulation produced by inductance change is in phase with amplitude modulation produced by the change in "Q" quality factor.

Viewed in another way, the inductances 5 and 6 and condenser 7 form a pi network through which oscillation voltage is transferred from anode 10 to control electrode 12. In usual forms of electron discharge oscillation generators, and in the type illustrated in Fig. 1, there need be only a part 50 of the voltage on the anode fed back to the control electrode, and, to maintain the generator in operation, that voltage so fed back must be maintained within certain limits. That is, if the amount of voltage fed back to the control electrode 55 is too little, the generator ceases the production of oscillations. With the illustrated oscillator, the feedback is maximum, and oscillation intensity correspondingly maximum, when the impedances of coils 5 and 6 are equal. Between these limits where continuous operation is maintained, the amount of voltage fed back from the anode to the control electrode has a substantial influence on the intensity of the oscillations.

60 The pi network 5, 6, 7 is effective to alter in substantial degree the amount of voltage fed back from anode 10 to control electrode 12 as the impedance of coil 5 changes. That is, variations of the impedance of coil 5 produce relatively large 65 changes in the ratio of voltage across coil 6 to the voltage across coil 5 when the impedance of coil 5 is lower than the impedance of coil 6. For this reason, it is preferred that the inductance of coil 5 be less than that of coil 6.

75 In the fundamental form of the present inven-

tion, the material of member 4 is conductive and of high specific resistance. To make it magnetic as well as conductive is useful when the member 4 need not be used in the presence of stray magnetic field and when it is desired to reduce or eliminate inductance change of coil 5 and corresponding change of oscillation frequency. Also, to make member 4 magnetic introduces hysteresis loss which aids the eddy current effect in member 4 to change the effective resistance of coil 5 and consequently to change the oscillation intensity. Cyclical change in inductance in element 5 causes a small amount of frequency modulation of the generated wave in tuned circuit 5, 6, 7 although only those components which produce amplitude modulation are detected on the grid leak resistance and amplified in device 10, 12, 13.

When the movable element 4 is constructed of magnetic and conductive material, movement of such element closer to coil 5 has a twofold effect on the inductance of that coil. Since element 4 has a greater permeability than that of air, the inductance tends to increase; since element 4 is conductive, the inductance tends to decrease. The net change in the inductance of coil 5 is equal to the difference between the opposing influences. At the same time, as element 4 approaches the coil, both the increased hysteresis loss and the increased eddy current loss operate to increase the damping resistance reflected in coil 5. In one arrangement incorporating an embodiment of the present invention, the permeability and specific resistance of element 4A (Figure 2) are so proportioned that substantially no net inductance change results from movement of the element with respect to the coil. Thus amplitude modulation of the oscillations generated in the tuned circuit 5, 6, 7 is effected with substantially no accompanying frequency modulation.

Figs. 3-5 show a preferred construction for mounting the vibratory member having the general reference numeral 4. In Figs. 3-5 the vibratory member is of the stainless steel type previously mentioned for reducing to a minimum the amount of extraneous 120 cycle hum introduced into the system and is of a thickness of approximately .004". The upper end thereof is embedded in a hard plastic base 24 which in turn is clamped between two halves 25, 26 of a plastic casing 27, the two halves being held together by cement or the like therebetween, or by bonding as by heat and pressure. Inductance coil 5 is mounted on coil form 28 which is fastened, for example by cement or the like, to the inside face of casing half 26 in magnetic relationship to member 4 with circular coil form 28 and the circularly shaped intermediate portion of member 4 substantially coaxial.

The free end of vibratory member 4 has a resilient L-shaped record contact stylus or needle 29 affixed thereon, for example by spot welding or the like, to give a desirable vertical compliance for the purpose of reducing needle chatter and record wear and for producing a desirable response curve which is substantially flat between 2000 and 4000 cycles per second with a sharp cutoff after 4000 cycles per second.

The phonograph pickup arrangement of Figs. 3-5 incorporated in a circuit such as shown in Fig. 1 has preferably a frequency response characteristic of the type shown in Fig. 6 wherein output voltage in the utilization device 2 is plotted as ordinate and frequency of the corresponding

voltage is plotted as abscissa. The sharp cutoff after 4000 cycles is due mainly to the fact that the vibratory member 4 in Figs. 3-5 is made to be mechanically resonant in its second mode at a frequency between 3000 and 4000 cycles per second. At this frequency the mode of vibration is such that the ends of the vibratory member remain substantially stationary and the middle portion adjacent the inductance element 5 vibrates with relatively large amplitude, so that the response at the frequency corresponding to this mode of vibration is large, and so that the response at increasingly higher frequencies is rapidly reduced. In order that the amplitude of vibration at the resonant frequency be not too large a damping element 30 such as a block of plasticized cellulose nitrate is fixed, as by heat and pressure, on the vibratory member at the upper end thereof in abutting relationship with the bottom surface of the base member 24. This material is preferred over ordinary rubber since it possesses more internal friction and less compliance per unit volume. Without the presence of a damping element 30 the characteristic curve 31 in full line in Fig. 6 is peaked in the manner indicated by the dotted line portion 32 thereof but with a suitably proportioned vibratory member 4 and damping element 30 the characteristic curve 31 is substantially flat in the range of 2000 to 4000 cycles per second. Without resonant effects in the mechanical vibratory member 4 the characteristic curve is substantially as indicated by the dotted line 33.

In another form of the invention shown in Fig. 3 the stylus or record engaging portion 3 at the end of vibratory member 4 may be straight instead of L-shaped as shown in the preferred embodiment in 4. Furthermore, instead of the upper end of the vibratory member 4 being embedded in a hard plastic base 24 as shown in the preferred embodiment in Fig. 3 the upper end of member 4 may be embedded in an elastic base 34 such as rubber. In such case the elastic body 34 is held between the two halves 25, 26 of casing 27 in the identical manner as shown in Fig. 3.

Inductance coil or element 5 has its opposite leads 35, 36 permanently connected respectively to metallic contact elements 37, 38 which are embedded in and extend from the inside to the outside of casing 27, the outer ends of contact elements 37, 38 being adapted to make good electrical and mechanical contact with corresponding contact elements 39, 40 embedded in and extending through the casing holder 41. Leads 42, 43 permanently fastened respectively to the upper ends of contact elements 39, 40 extend through at least part of the tone arm 44 to the appropriate terminals 45, 46 in the oscillator circuit of Fig. 1.

The replaceable casing 27 which may be sold as an article of commerce contains in a unitary structure the vibratory member 4 and coil 5 magnetically coupled thereto in predetermined spaced relationship and is held as a unit snugly in the casing holder 41 by projections 47, 48 engaging correspondingly shaped depressions (not shown) in the walls of casing holder 41 and by contact projections 49, 50 engaging correspondingly shaped depressions in contact elements 39, 40.

The casing holder 41 is pivotally mounted about the axis of fixed pin 51 in a pair of arms 52 disposed on opposite sides of the casing holder 41, each arm having one end thereof fastened to the tone arm, for example by screw 53, and the other end thereof circularly formed to provide a

bearing member with pin 51. Arms 52 may be flexible but are preferably non-flexible.

The casing holder 41 is normally spring biased downwardly for rotation about the axis of pivot pin 51 by coil spring 54 having its ends fastened to tone arm 44 for example by screw 55 and an intermediate portion 56 engaging holder shoulder 57 to press the holder 41 downwardly in the direction of counterclockwise rotation about pin 51.

The coil spring 54 is made sufficiently flexible such that the pickup unit is protected against injury in case the tone arm is dropped inadvertently, carelessly, etc. In such case the pickup unit including the casing holder 41 is deflected upwardly against the action of weak spring 54 so that the heel of casing 27 engages the record, arm 59 being fastened to the tone arm for example, by screw 53 to serve for a stop for excessive movement of casing holder 41 the free end of arm 59 is provided with a piece 58 of felt or other cushioning material to prevent undesirable rattling of casing holder 41 against arm 59. Protection is also afforded to the L-shaped stylus by extending the casing halves 25, 26 sufficiently far downwardly such that when more than a predetermined force is applied to the stylus, it moves upwardly within the space confined by the casing halves 25, 26. Since the ends of arms 52 and 59 are both held by the same screw 53 it is obvious that if desired the arm 52 may form an integral extension of arm 59. This retractability feature is specifically claimed in United States Patent No. 2,444,218, issued June 29, 1948, to C. W. Carnahan, which patent is assigned to the present assignee.

The oscillator-detector arrangement shown in Fig. 1 is preferred but other arrangements may be utilized; for example, the arrangements of Figs. 8 and 9 may be utilized to carry out certain aspects of the present invention. The frequency of oscillation is in the order of 6 megacycles.

In Fig. 8 the rectification action between grid 12 and cathode 13 is not used as in the preferred form but a separate diode demodulator anode 60 is used with cathode 13. Amplitude modulated radio frequency signals are applied from the anode 10 to the diode anode 60, through condenser 61, the cathode 13 being grounded with the result that only voltages of frequencies corresponding to the amplitude modulation components are present in large magnitude between anode 60 and ground.

The detected voltage of audible frequency between anode 60 and ground appears across resistance 62, connected between anode 60 and cathode 13, and is amplified through an electron discharge amplifier device including cathode 13, a control electrode 63 and an anode 64, a load 2 being connected between cathode 13 and anode 64 for further amplification or utilization.

In Fig. 8 certain elements are like those shown in Fig. 1 and are given like reference numerals. That is, anode 60 is connected through resistance 21 and condenser 22, in series, to control electrode 63 and resistance 20 and condenser 23 are connected in shunt between control electrode 63 and cathode 13. Anode 64 is connected through resistance 19 to the positive terminal of source 15. These elements function in the same manner as those shown in Fig. 1.

It is desirable that, where a separate diode detector is used, the two amplifying discharge devices and one diode detector be in one envelope and have a single cathode, since cathode heating current and connections are thereby minimized.

It is of substantial advantage to use such a separate diode detector arrangement because of greatly increased detection efficiency.

When detection is accomplished in the oscillator, as in Fig. 1, a part of the detection is accomplished in grid 12 by rectification between that grid 12 and cathode 13, and a part is accomplished by what is called "plate bend detection." The demodulated voltages appearing on anode 10 from these two sources are, however, in opposite phase, with the result that the detection is not highly efficient. Also the amplification of the audio signal from grid 12 to anode 10 is not highly efficient since limitations are imposed on the discharge device by its operation as an oscillator. Nevertheless, the arrangement of Fig. 1 is desirable where it be desired to provide a very minimum of parts at the sacrifice of some gain, since amplification from grid 12 to anode 10 of the rectified signal is more than enough to offset the relatively inefficient detection attained when both grid rectification and plate bend detection are present.

In Fig. 9 the grid rectification action between grid 12 and cathode 13 is not used as in the preferred form but instead there is used a separate triode demodulator device 65 operating on the non linear portion of its plate current-grid voltage characteristic near a point thereon corresponding to plate current cutoff. Amplitude modulated waves are transferred from the junction point of elements 6, 7, 9 to the grid 66 of device 65, the cathode 67 thereof being grounded through the parallel circuit comprising resistance 68 and condenser 69, and the anode 70 being connected to the positive terminal of the anode supply source 15 through resistance 71. The amplitude modulation components of audible frequency appearing at anode 70 are transferred through isolating condenser 72 to an amplifying and/or utilization device. This arrangement has the advantage of providing efficient detection and voltage gain, and the two discharge devices may be in the same envelope.

An important feature of the present invention embodied in the arrangements of Figs. 1, 8 and 9 is that but one single tuned circuit is utilized to determine the frequency of oscillation of the generated superaudible frequencies and no other tuned circuit is utilized, either in the oscillation generator, the detector, or any amplifier between the oscillation generator and detector. This feature is important since there is no likelihood of the detection of any frequency modulation components due to mistuning, drift, etc., occasioned in the use of a plurality of tuned circuits. In those arrangements herein where frequency modulation components may be developed they have no influence on the audio system since (1) they are not detectable and (2) they are filtered out along with the voltages of superaudible frequency. In brief, the use of a single frequency determining circuit avoids any necessity for alignment which would be necessary were a plurality of tuned circuits used and it is not necessary to take the special precautions which would then be necessary to avoid detuning between several circuits which would be produced by eccentricity of record 1 forcing large inductance changes in coil 5 or by frequency instability of the oscillator.

While particular embodiments of the present invention have been shown and described, it will be obvious to those skilled in the art that changes and modifications may be made without departing from this invention in its broader aspects.

and, therefore, the aim in the appended claims is to cover all such changes and modifications as fall within the true spirit and scope of this invention.

I claim:

1. Signal translating apparatus including: an electron discharge device having a cathode, an input electrode, and an output electrode; a single frequency-determining circuit coupled between said input electrode and said output electrode to constitute with said device an oscillation generator for producing oscillations of superaudible frequency, said circuit including the parallel combination of a condenser and a pair of serially connected inductance coils; a connection from the junction of said coils to said cathode; a transducer including a conductive element magnetically coupled to one of said coils to reflect therein a damping resistance having a magnitude determined by the space relation of said element and said one coil for amplitude modulating said oscillations in response to relative movement between said element and said one coil; a condenser and a grid leak resistor included in said oscillation generator and coupled to said cathode and to said input electrode for detecting said modulated oscillations; and an audio frequency load impedance coupled to said cathode and to said output electrode for deriving an amplified audio frequency output signal in response to the detected amplitude modulation of said oscillations.

2. Signal translating apparatus including: an electron discharge device having a cathode, an input electrode, and an output electrode; a single frequency-determining circuit coupled between said input electrode and said output electrode to constitute with said device an oscillation generator for producing oscillations of superaudible frequency, said circuit including the parallel combination of a condenser and a pair of serially connected inductance coils; a connection from the junction of said coils to said cathode; a transducer including a magnetic and conductive element magnetically coupled to one of said coils to reflect therein a damping resistance having a magnitude determined by the space relation of said element and said one coil for amplitude modulating said oscillations in response to relative movement between said element and said one coil, the permeability and specific resistance of said element being so related that said relative movement produces substantially no net change in the inductance of said one coil; a condenser and a grid-leak resistor included in said oscillation generator and coupled to said cathode and to said input electrode for detecting said modulated oscillations; and an audio frequency load impedance coupled to said cathode and to said output electrode for deriving an amplified audio frequency output signal in response to the detected amplitude modulation of said oscillations.

3. A record player including: an electron discharge device having a cathode, an input electrode, and an output electrode; a single frequency-determining circuit coupled between said input electrode and said output electrode to constitute with said device an oscillation generator for producing oscillations of superaudible frequency, said circuit including the parallel combination of a condenser and a pair of serially connected inductance coils; a connection from the junction of said coils to said cathode; a replaceable transducer unit comprising one of said coils and a vibratory element having a conductive portion of high specific resistance ma-

terial magnetically coupled to said one coil and carrying a stylus adapted to track the undulations of a rotatable record disc to reflect in said one coil a damping resistance having a magnitude determined by the space relation of said conductive portion and said one coil for amplitude modulating said oscillations in response to vibration of said stylus; a condenser and a grid-leak resistor included in said oscillation generator and coupled to said cathode and to said input electrode for detecting said modulated oscillations; and an audio frequency load impedance coupled to said cathode and to said output electrode for deriving an amplified audio frequency output signal in response to the detected amplitude modulation of said oscillations.

4. A record player including: a triode having a cathode, a control grid, and an anode; a single frequency-determining circuit coupled between said grid and said anode to constitute with said triode an oscillation generator for producing oscillations of superaudible frequency, said circuit including the parallel combination of a condenser and a pair of serially connected inductance coils; a connection from the junction of said coils to said cathode; a replaceable transducer unit comprising one of said coils and a vibratory element having a conductive portion of high specific resistance material magnetically coupled to said one coil and carrying a stylus adapted to track the undulations of a rotatable record disc to reflect in said one coil a damping resistance having a magnitude determined by the space relation of said conductive portion and said one coil for amplitude modulating said oscillations in response to vibration of said stylus; a condenser and a grid-leak resistor included in said oscillation generator and coupled to said cathode and to said grid for detecting said modulated oscillations; and an audio frequency load impedance coupled to said cathode and to said anode for deriving an amplified audio frequency output signal in response to the detected amplitude modulation of said oscillations.

5. A record player including: a triode having a cathode, a control grid, and an anode, a single frequency-determining circuit coupled between said grid and said anode to constitute with said triode an oscillation generator for producing oscillations of superaudible frequency, said circuit including the parallel combination of a condenser and a pair of serially connected magnetically independent inductance coils; a connection from the junction of said coils to said cathode; a replaceable transducer unit comprising one of said coils and a vibratory element having a conductive portion of high specific resistance material magnetically coupled to said one coil and carrying a stylus adapted to track the undulations of a rotatable record disc to reflect in said one coil a damping resistance having a magnitude determined by the space relation of said conductive portion and said one coil for amplitude modulating said oscillations in response to vibration of said stylus; a condenser and a grid-leak resistor included in said oscillation generator and coupled to said cathode and to said grid for detecting said modulated oscillations; and an audio frequency load impedance coupled to said cathode and to said anode for deriving an amplified audio frequency output signal in response to the detected amplitude modulation of said oscillations.
